UNITED STATES PATENT OFFICE

SAMUEL I. BERGER, OF NEWARK, NEW JERSEY

MECHANICAL TOY

Application filed March 3, 1927. Serial No. 172,232.

The toy of the present invention is of the type in which a miniature airplane, normally resting on the ground is connected to one end of a normally inclined counterweighted lever rotatably fulcrumed intermediate its ends on the top of a stationary column. The airplane motor drives a toy propeller which moves the plane over the ground at such a speed that the centrifugal force developed, coupled with the lifting action of the propeller is sufficient to overcome gravity and cause the plane to rise and fly in a circular path, turning the lever about the column. This action is, of course, assisted in large measure by the counterweight which is preferably so proportioned that even a small centrifugal force will tend to swing the lever to horizontal position.

One object of the invention is to provide a toy of this character in which the counterweight simulates an aircraft, so that when the device is in motion there will appear to be two aircraft flying in circular paths about the central column, which may be conveniently designed to simulate a mooring mast or lighthouse if desired.

Another object of the invention is to provide an improved simplified construction of airplane which will be realistic in appearance. Another object of the invention is to improve and simplify the construction of the lever and its rotatable fulcrum. Preferably the lever carries its own fulcruming pin adapted to be removably mounted in a socket in the column, and the use of a projecting pin in the column which might seriously injure a child falling upon it is entirely avoided.

Further and more general objects of the invention are to provide a toy of simple practical construction, which will be rugged, durable and efficient in use, which will provide amusement and diversion for both old and young observers, which may be conveniently set up and operated by a child and which is well suited to the requirements of economical manufacture.

The invention may be more fully understood from the following description together with the accompanying drawings, which are illustrative of only one of the preferred em-

bodiments of the invention and not to be construed in a limiting sense.

In the drawings

Fig. 1 is a view in side elevation of the toy with the airplane at rest and parts of the column broken away and in section to expose its construction. The dotted lines indicate the positions assumed by the two toy aircraft and the lever when the toy is in operation.

Fig. 2 is a fragmentary plan view of the lever,

Fig. 3 is a fragmentary longitudinal sectional view therethrough,

Fig. 4 is a top plan view of the motor driven airplane, on a larger scale,

Fig. 5 is a longitudinal sectional view therethrough,

Fig. 6 is a side elevational view of the other aircraft with parts of the body broken away to expose the counterweight,

Figs. 7 and 8 are transverse sectional views on the lines 7-7 and 8-8 respectively of Fig. 6; and

Fig. 9 is a fragmentary perspective view showing an alternative form of the airplane.

Referring to Fig. 1 in a general way I have used the numeral 10 to designate the central supporting column on the top of which is rotatably fulcrumed the lever 11. Detachably connected to opposite ends of the lever are the motor driven toy airplane 12 and the counterweighted toy aircraft 13, the latter preferably simulating a dirigible and being slightly lighter than the former which normally rests upon the ground and maintains the lever in the tilted position to elevate dirigible 13.

Supporting column

This device (Fig. 1) may be of any desired construction, although I have devised a very simple and satisfactory method of constructing it to simulate a mooring mast or lighthouse. A relatively wide sheet metal base plate 15 mounts a conically tapering hollow body or column 16 preferably of circular shape in cross section and at its lower edge having tongues 17 passed through slots in the base plate and twisted to lock the plate and the column together. The relatively

wide base renders it difficult to tip the column over. A cap piece 18 closes the top of the column and a substantially hemispherical hollow dome member 19 is mounted on the top of the cap. The cap may be attached to the dome and column by the tongue and slot connections so well known in the sheet metal toy art and the cap and dome are formed with aligned central openings 20. An annular member 21 encircling the column 16 near its upper end may be upwardly flanged at 22 and may simulate the observation platform or bridge of a mooring mast or lighthouse, the resemblance being enhanced by suitable surface decoration (not shown) on the various parts as will be well understood.

Lever

The lever 11 (Figs. 1, 2, and 3) is formed of two preferably identical sections 23, 23 each comprising a length of channelled sheet metal with the channels facing downwardly when the lever is in applied position. The channel forming flanges terminate short of the outer ends of the sections while extended ends of the intermediate or web portion of the channel pieces may be transversely bent to define hooks 24 adapted to receive the aircraft 12 and 13. At the opposite ends of the lever sections the channel forming flanges are extended to define ears 25 one ear of each pair being longer than the other and coacting with the lower side of the web of the opposite section to prevent pivotal movement of the sections in one direction about the pivot pin 26 which is passed through the four aligned and apertured ears 25. Thus the lever may be folded upwardly for compactness in storage and handling but will serve as a rigid bar being self sustaining against downward folding movement when mounted on top of the column.

The flattened apertured end 28 of a fulcruming pin 29 receives the pivot pin 26 which is enlarged at its ends 26' to prevent separation of the parts. The rounded end of the pin 29 is adapted to be entered into the aligned openings 20 in the cap and dome of the column, the walls of said openings providing a double bearing for the pin. The extent to which the pin 29 may be inserted is limited by burrs or tits 30 struck therefrom.

Motor driven toy airplane

A single longitudinally tapered sheet of metal, Figs. 4 and 5, cut to the desired shape, is bent along longitudinal lines to define the top 31 and sides 32 of the airplane body. The bottom of the body is substantially open, save for a pair of inwardly presented flanges 33 integral with the lower edges of the sides. The front end of the body is closed by a nose cap 34 which with one arm of an interiorly arranged generally U-shaped bracket 35 provides bearings for a propeller shaft 36 on

the outer end of which is fixed a propeller 37.

Depending ears 38 and 39 integral with the sides 32 of the body provide mountings for the wheel axles 40, 41. A pair of traction wheels 42 are mounted on the front axle 40 while a single steering and traction roller 43 is turnable freely on the rear axle 41.

The plane is of the monoplane type, a wing forming sheet 44 being bent at the desired angle to give the proper lifting action and at its center following the contour of and being secured to the forward portion of the body top 31 by tongues 45 at the upper ends of bracket arms 35. The wing may be corrugated as at 44a to strengthen it against bending strains. A plate 46 mounted on top of the wing has an upstruck portion 47 simulating the head and shoulders of a pilot and an upstruck slotted tab portion 48 adapted to be engaged with one of the hooks 24 of the lever 11.

The body is of the usual tapered formation and secured upon the rear end thereof is a tail forming sheet 49 and a vertical rudder portion 50.

The motor mechanism may be more or less conventional and has been illustrated as including a winding shaft 51 the forward end of which turns in the bracket 35 and the rear end of which is borne in a generally similar concealed bracket 52 depending from the top of the body. The rear end of this shaft is extended and bent to provide a readily accessible winding key 53. Shaft 51 mounts a drum 54 about which is wound a helical torsional motor spring 55, this spring being anchored to the rear end of the drum 54 and to a gear 56 mounted on the forward end of the shaft 51. Any suitable arrangement of the well-known type for enabling the spring 55 to be wound by the key 53 and then to turn the gear 56 may be utilized. A countershaft 57 journaled in the bracket 35 carries a pinion 58 meshing with the gear 56 and also carries a gear 59 meshing with a pinion 60 on the propeller shaft 36. There is thus provided a train of speed multiplying gears between the motor and the driven propeller.

Counterweighted aircraft

This device (Figs. 6, 7, and 8) as suggested above is preferably constructed to simulate the appearance of a dirigible and is formed of a pair of identical elongated dished sections 65 connected by overlapping tongues 66 at their edges and cooperatively defining a hollow body within which is concealed a counterweight such as the bar 67. The basket portion of the blimp is formed by cooperating depending extensions 68 of the sections 65. Alined upstanding slotted tabs 69 secured together by bent-over tang 69' provide a means of attachment to the lever hook 24.

Rudder sections 70 integral with the body sections 65 may be used if desired and a tail

fin forming plate 71 of general V shape in cross section is secured by passing it through aligned slots 72 in the body.

5

Operation

In operation the column 10 is set up upon any suitable flat surface such for instance as the table 90, the lever 11 is unfolded and the fulcrum pin 29 inserted in the openings 20. Dirigible 13 is hooked on one end of the lever 11. The motor of the airplane 12 is wound and the plane engaged with the other end of the lever, the weight of the airplane 12 slightly predominating so that it will rest 15 on the table 90 and elevate the dirigible as seen in Fig. 1.

As the propeller 37 (which has been manually held against rotation while winding the motor and attaching the plane to the lever) 20 is released it will act to draw the airplane 12 forwardly moving it in a circular path over the table about the column 10 as a center and initiating rotative movement of the lever 11 on its fulcrum. Most of the weight 25 of the airplane 12 is sustained by the counterweighted dirigible 13 so that the propeller will have but little friction to overcome when starting and maintaining rolling movement of the wheels 42, 43 over the surface of the 30 table.

The centrifugal force developed by the circular travel of the airplane coupled with the slight lifting action of the propeller on wing 44 causes the plane to gradually rise 35 above the surface of the table until the lever 11 assumes the substantially horizontal position illustrated in dotted lines in Fig. 1. Rotation of the toy will continue with the lever in this position until the motor slows 40 down and the plane loses momentum at which time the plane will gradually settle down onto the surface from which it rose.

The taking off, flying and landing of the plane is very realistic and amusing to watch. 45 The use of the dirigible adds to the natural appearance of the toy particularly while the plane is in flight.

In Fig. 9 is shown an alternative form of airplane embodied as a bi-plane instead of 50 a monoplane. For this purpose, the fuselage 31' has its extension ears 38' extending downward through corresponding slots 38² in the lower wing w. Spars 75 are struck up from the lower wing, leaving openings 76 therein, 55 said spars stiffened by bending longitudinally for a channel beam conformation, which includes lateral wings 77. The upper ends of the spars are attached to the upper wing 44', preferably by soldering (not shown).

60 In the present embodiment I have also indicated a novel form of brake, which, of course, is applicable alternatively to the monoplane construction of Figs. 4 and 5, or the bi-plane construction of Fig. 9. This brake 65 comprises a length of wire 78 extending

longitudinally within the fuselage and protruding rearward of the fuselage through an elongated slot 79, the exterior part being conformed as a handle or operating member 80. The forward end of the brake wire is formed as a reversely bent loop 81 extending through an elongated slot 82 in the forward end of the fuselage body, said loop 81 extending when the brake handle is pushed to the operative position shown, in the path of rotation of the propeller 37'. When the handle 80 is pushed back to the opposite extremity of its slot, the end of the forward part 81 is drawn out of the path of rotation of the propeller. The forward end of the brake member being rounded will not become interlocked with the propeller should it be advanced when a part of the propeller is in the path thereof. The rear or handle end of the operating member frictionally engages the fuselage body so that said brake member will be frictionally or impositively held in any setting thereof. With the brake construction shown, it will be seen that the winding of the motor is facilitated and the airplane body can be deposited upon the ground on starting the toy, without having to hold the propeller, the latter being released by simply drawing the brake handle 80 rearwardly.

Obviously various structural modifications might be resorted to within the spirit and scope of the appended claims.

Having thus described my invention, what I claim as new and desire to secure by Letters-Patent is:

1. A toy of the class described, including a central supporting column, a tilting lever rotatably fulcrumed on the upper end thereof, said column having a cap and dome at the top with vertically aligned perforations therein, a revoluble pin in said perforations, a horizontal pivot connecting said lever and pin, a toy motor-driven airplane detachably engaged with one end of the lever, and a counterbalancing toy aircraft carried by the other end of the lever.

2. A toy of the class described, including a central supporting column, a tilting lever rotatably fulcrumed on the upper end thereof, said column having a cap and dome at the top with vertically aligned perforations therein, a revoluble pin in said perforations, a horizontal pivot connecting said lever and pin, a toy motor-driven airplane detachably engaged with one end of the lever, and a counterbalancing toy aircraft carried by the other end of the lever, said aircraft comprising a hollow sectional body simulating a dirigible, and a counterweighting bar in the body.

3. A toy of the class described, including a central supporting column, a tilting lever rotatably fulcrumed on the upper end thereof, said column having a cap and a dome at the top with vertically aligned perfora-

tions therein, a toy motor-driven airplane detachably engaged with one end of the lever, and a counterbalancing toy aircraft carried by the other end of the lever, a fulcrum pin carried by the central part of said lever and adapted to be inserted in said perforations at the top of the column, the lever being pivoted to said pin.

4. A toy of the class described, including a central supporting column, a tilting lever rotatably fulcrumed on the upper end thereof, said column having a cap and a dome at the top with vertically aligned perforations therein, a toy motor-driven airplane detachably engaged with one end of the lever, and a counterbalancing toy aircraft carried by the other end of the lever, a fulcrum pin carried by the central part of said lever and adapted to be inserted in said perforations at the top of the column, said pin including means to limit the extent of its insertion, the lever being pivoted to said pin.

Signed at Newark, in the county of Essex and State of New Jersey, this 18th day of 25 February, A. D. 1927.

SAMUEL I. BERGER.
